ATTORNEY

UNITED STATES PATENT OFFICE

149,230

DESIGN FOR A FLASHLIGHT OR LIKE ARTICLE

Fred Schlotterbeck, New York, N. Y., assignor to Guth, Stern & Co., Inc., a corporation of
New York

Application January 24, 1947, Serial No. 136,356

Term of patent 3½ years

(Cl. D48—24)

To all whom it may concern:

Be it known that Fred Schlotterbeck, a citizen of the United States and resident of New York city, in the county of Queens, State of New York, has invented a new, original, and ornamental Design for a Flashlight or Like Article, of which the following is a specification, reference being had to the accompanying drawing, forming part thereof, in which Fig. 1 is a front elevational view of a flashlight showing my new design, and Figs. 2 and 3 are top and bottom end views, respectively, thereof.

I claim:

The ornamental design for a flashlight or like article, as shown.

FRED SCHLOTTERBECK.
